UNITED STATES PATENT OFFICE.

GEORGE E. BARNHART, OF PASADENA, CALIFORNIA.

GOLF-CLUB TESTING MACHINE.

Application filed April 30, 1927. Serial No. 187,976.

Although my present invention is capable of testing various types of rods or shafts, as to their ability to withstand such strains (producing either a torque or by a longitudinal bending operation, or both) as may result from sudden contact with an obstruction, said invention is referred to as a "golf club testing machine", for the reason that it is a particular object of this invention to provide means for approximately imitating the various strokes by which golf balls may be driven, and to test the ability of golf shafts to survive such use or abuse as they may encounter in the hands of golfers.

It is an object of my invention to provide means for securing a golf club eccentrically, and preferably at a plurality of points, relatively to a shaft or shaft section which is provided with means for imparting a uniform or a non-uniform rotational movement thereto; and, in preferred embodiments of my invention, the said shaft being inclined with reference to a horizontal axis and disposed above a suitable means for the support of one or more golf balls (or equivalent movable obstructions) I provide means for varying the speed at which said shaft is rotated, means for varying the inclination of said shaft, and means for suitably supporting one or more golf balls (or equivalent obstructions) in such manner that the same shall be successively or repeatedly struck, during successive strokes of a golf club, as produced by mechanical means having the indicated general character.

Other objects of my invention, including the provision of a suitable mechanical train, for driving the mentioned shaft section at various speeds from a suitable motor, and preferably including also means for so gripping a shaft as to obviate marring the same, and including also means whereby a series of golf balls or the like, may advance in proper synchronism with reference to the rate of rotation of the mentioned shaft, may be best appreciated from the following description of an illustrative embodiment of my invention, taken in connection with the appended claims and the accompanying drawings, in which

Fig. 1 may be referred to as a side elevational view, with parts broken away, of a complete machine embodying my invention.

Fig. 2 is a top view, corresponding to Fig. 1, but taken from the direction of arrow 2, 55 with optional parts omitted and other parts broken away.

Fig. 3 is an enlarged detail sectional view, taken substantially as indicated by the line 3-3 of Fig. 1. 60

Fig. 4 is a vertical sectional view, taken substantially as indicated by the broken line 4-4 of Fig. 1.

Fig. 5 is a detail sectional view, on a larger scale, taken substantially as indicated 65 by the line 5-5 of Fig. 1.

Fig. 6 is a detail view, taken substantially as indicated by the arrow 6 of Fig. 5, but omitting an optional gear-shifting or speed-changing organization shown only in Fig. 1. 70

Fig. 7 is a detail sectional view, similar to Fig. 5, but taken substantially as indicated by the line 7-7 of Fig. 1.

Fig. 8 is a sectional detail view, taken on a still greater scale of enlargement, substantially as indicated by the lines 8-8 of Figs. 1 and 2. 75

Fig. 9 is a detail sectional view, taken substantially as indicated by the line 9-9 of Fig. 8. 80

Figs. 10 and 11 are respectively detail views, showing alternative forms of ball holders, taken substantially as indicated by the line 10-11 of Fig. 1.

Fig. 12 is a vertical sectional detail view, 85 comparable with Figs. 10 and 11, but showing an alternative construction hereinafter referred to.

Referring to that specific embodiment of my invention which is chosen for purposes 90 of illustration, and mentioning first the major parts thereof, I show a pivoted main frame 11 as secured above a base 11' by means comprising a horizontal pivot shaft 13 and a built-in jack 14,--said main frame 95 being employed to support an electric motor 15, indirectly driving a uniformly-rotated shaft 12. Said main frame provides fixed bearings not only for said shaft but for an intermediate shaft 16 (to which uniform 100 motion may be transmitted by means such as pulleys 17 and 18, interconnected by a belt 19) and said frame may also provide adjustable bearings 20, 21, for a driven shaft system 22 including a crank-driven section 23, 105 a brake-carrying section 24,--a clutch-

driven section 25 being shown as interposed and a clamp-carrying sleeve 26 being mounted upon the brake-carrying section and provided not only with a slip-limiting 5 connection but with means for the releasable retention of a golf club or other shaft 27.

Although it will be obvious that uniform motion might be imparted to the intermediate shaft 16 by alternative means, I show a motor shaft 28 as carrying a gear 29, engaging a gear 30 on shaft 12; in order conveniently to vary the rate of rotation of the pulley 17, a shaft section 12', when not directly rotated by the gear 30, or its equivalent, may be subject to control of a gear-shifting organization 30', manipulable by a lever 31; and I show the belt 19 as tensioned by means comprising an idler 33.

20 In order to provide for either a uniform or a non-uniform rotation of the crank-driven shaft section 23, comprised in the driven shaft system 22, I may employ means such as an arm 32, rigidly secured on the intermediate shaft 16 and provided with a long slot 34, for the reception of a roller-carrying wrist pin 35, carried by a crank 36 on said crank-driven shaft section 23. Frame elements 37 and 38, carrying respectively the mentioned adjustable bearings 20 and 21 are shown as provided with longitudinal slots 39, 40, of sufficient length to permit the driven shaft system 22 to be disposed either concentrically with the intermediate shaft 16, in order to receive uniform rotational movement therefrom, or to permit said driven shaft system to be eccentrically disposed, to any distance less than the length of the crank 36,—this construction making 40 it possible to impart, within a wide range, any desired uniform or variably accelerated rotary motion to the crank-driven shaft section 23; and, in order to permit a selection of any desired part of a rotational cycle for transmission to the brake-carrying section 24, interposing any suitable clutch element 41, I may employ means such as cam-carrying gear 42, driven by a gear 43 on shaft section 23, to impart movement to a 45 clutch operating lever 44, shown as provided with a cam finger 45, engageable by a cam 46, adjustably or otherwise secured on the gear 42. The lever 44 is shown as provided with a slot 47, corresponding in 50 length with the mentioned slots 39 and 40, in order to permit said lever to be adjusted, relatively to a pivot pin 48, consistently with the adjustment of bearings 20, 21; and, in order that the clamp-carrying sleeve 26 55 may be started and stopped without undue strains and duplicating similar golf player's movements, the shaft section 24, on which said sleeve is movably mounted, may be provided with not only a brake organization 60 comprising a drum 49, but with a slip-limit-

ing frictional engagement organization comprising discs 50 and 51,—the latter being rigidly connected with the sleeve 26.

In order to assure satisfactory operation of the mentioned brake organization, providing a hub 52 (integral with the drum 49 and shown as secured by a key 53) with an adjustable or other cam finger 54, and surrounding said drum by a brake band 55, I may rigidly secure one end of said band to a fixed bracket 56, to which a cam lever 57 is pivotally secured,—this lever being shown as provided not only with a cam 58, engageable by the cam finger 54, but with a band-tightening roller 59. As best shown in Fig. 7, the free end 60 of the band 55 may be constantly pressed toward a drum-releasing position by means such as a compression spring 61, constantly engaging a bracket 62,—which may provide an inclined surface 63, 85 for engagement by the roller 59. It will be seen that the relationships between the parts referred to are such that whenever the cam finger 54 engages the cam 58, the brake band 55 is tightened on the drum 49, thereby 90 bringing the shaft 24 to a stop; and that, by properly shaping and positioning the cam finger 54, the described brake may be applied in a properly-timed relationship with reference to the automatic shifting of the 95 clutch lever 44, or its equivalent, to impart a desired movement to sleeve 26.

In order, however, to permit the sleeve 26, or its equivalent, momentarily to continue in motion even after the shaft section 24 is 100 brought to a stop, or to lag when said shaft begins to revolve (although thereafter positively driven) providing one or both of the discs 50, 51 with a surface or material adapted to assure frictional engagement 105 therebetween, and constantly pressing said surfaces together by means such as a compression spring 64 (see Figs. 1 and 2) retained by means such as a nut 65, I may provide the disc 50 (shown as integral with the 110 mentioned hub 52 carrying the brake drum 49 and as smaller than the companion disc 51) with a stop element 66, movable between adjustable stops 67 and 68, provided on the disc 51,—the latter being shown as provided 115 with a row of peripheral holes 69 to facilitate adjustment of the mentioned stops thereon.

Although any suitable means might be employed for releasably clamping a golf 120 club shaft relatively to the sleeve 26 and to effect the proper centrifugal force on the club shaft by changing its direction, I show said sleeve as carrying a substantially circular plate 70 on which a shaft-receiving 125 channel organization 71 is pivotally secured by means of a central pin or projection 72, entering a corresponding depression 73 in said plate. The pin 72 is shown as integral with a bar 74 to which a trough 130

member 75, carrying a cushion 76 may be secured by bolts or screws 77—counterpart trough members 78, carrying cushions 79, being movable by screws 80, extending 5 through separate C-shaped elements 81. The inner ends 82 of said C-shaped elements are shown as adapted to engage the back surface of the plate 70, the outer ends or arms 83 thereof being threaded for reception of the screws 80.

By means of the general character described, it will be seen that a golf club shaft, or its equivalent, may be grasped at any suitable points, near the upper or 15 larger end thereof, and disposed either at right angles to the longitudinal axis of sleeve 26 or at any desired inclination thereto, as suggested by the dotted outlines 27' and 27'', Fig. 1.

It being a primary object of my invention to provide means for closely counterfeiting any one of a great variety of strokes to which golf clubs may be subjected in ordinary use (or abuse) I may interpose 20 an additional gear-shifting organization 30'' (to make one-fourth, one-half, one-third, or other portions of a full stroke), this being shown as provided with a shift lever 31' and as disposed between the brake-carrying shaft section 24 and clutch-carrying shaft section 25—shown as chambered to provide a bearing for one end of the crank-driven shaft section 23; and I prefer not only to provide means, such as the mentioned jack 14, for varying the inclination of the mentioned driven shaft system, coaxial with the sleeve 26, but to provide means for supporting ordinary golf balls; or other yieldable obstructions, in the path 25 through which heads or impact members 84, carried by golf clubs or other shafts, may be swung by means similar to those herein described; and, for the purpose here referred to, I may provide, in front of the jack or jacks 14 (shown as comprising a body 85, pivoted at 86 and a screw 87, pivotally connected at its upper end and adjustable by a nut 88) an obstruction-carrying subsidiary frame 89. The frame 30 89 is shown as comprising extensible legs 90, 91, supporting horizontal elements 92 and 92', shown in the form of angle bars. Near the respective ends of the latter, I may secure bearing blocks 93, 93', for short 35 shafts 94, 95, carrying sprockets 96, 97—over which may extend a sprocket chain 98, carrying "tees" or equivalent supports for golf balls 99 or equivalent yieldable obstructions.

To drive one of the sprockets 96, 97, I may employ (see Figs. 1 and 2) means such as a gear 100 upon the shaft 16 and a gear 101 upon the shaft 94,—any suitable transmission mechanism being interposed therebetween. For example, assuming the last

mentioned gear to be a bevel gear engageable by a corresponding bevel gear 102, the latter may be secured upon end portions 103 of a sectional shaft comprising an extensible main section 104 and a sprocket-carrying section 105,—the end sections 103 and 105 being respectively supported by bearing brackets 106 and 107, and connected with the central section 104 by means such as gimbal bearings or universal joints 108, 75 109; and motion may be transmitted from the gear 100, or its equivalent, to a sprocket 110, on the shaft section 105 by means such as a gear 111, engaged by the gear 100 and carried by a shaft 112, extending through 80 bearing brackets 113 and 114 and provided with a sprocket 115,—a sprocket chain 116 being carried over sprockets 115 and 110.

It will be understood that the dimensional ratios between the gears in the described train are intended to be such as regularly to advance one of the golf balls 99, or any desired yieldable obstructions (when a series of such obstructions are employed) into such a position that the shaft 27, or any impact member 84 provided thereon, shall suitably encounter the same, to counterfeit a particular stroke; and, depending upon whether actual golf balls or metallic or other hard balls 99' are 95 to be advanced by chain 98, or its equivalent, I may provide on said chain either resilient tees, comprising spiral springs somewhat as suggested at 117, Fig. 10, or I may employ rigid (metallic or wooden) 100 tees, as suggested at 118, Fig. 11; or, in case the replacement of actual balls is to be obviated, I may secure directly to the horizontal frame elements 92, or to a member thereon, a plate 119,—to support a tube 105 120, or its equivalent, adapted to serve as a housing for a resilient or other retracting element 121, directly or indirectly carrying a special golf ball or other yieldable obstruction 99''. The plate 119 is shown as secured to the elements 92 and 92' by screws or bolts 122 and the resultant or extensible element 121 is shown as secured by an eye 123 to a cap or terminal element 124, at the lower end of the tube or housing 120,—the upper end of said resilient or extensible element being secured to the ball 99'' (presumably formed of rubber) by means of an eye bolt 125, extending through a spherical spacing element 126, seating 110 within or upon a convex or other shoulder 127, at the upper end of the tube or housing 120.

Although the general mode of operation of my shaft-testing device has been indicated 115 in connection with the description thereof, I especially emphasize the following facts:

My described testing machine having been designed primarily for use in ascertaining 120 the behavior of hollow metallic golf club 130

shafts, a club or other shaft which is to be tested may be secured at any desired distance from an end thereof and at any desired angle relatively to the plate 70 on the sleeve 26; 5 and said club or other shaft may be swung, at a rate and in a manner which is subject to variation by a shifting of the lever 31 and/or the lever 31' and/or by variation in the distance between shaft 16 and the ro- 10 tational axis of shaft section 23,—a preferred portion of each uniform or variable cycle of rotation imparted to this shaft section being transmitted through the cam-controlled clutch 41 to one of the concentric driven 15 shaft sections supported wholly or partly by bearings 21. The cooperating discs 50, 51, and parts thereon, essentially constitute a preferred means of permitting a limited initial and final relative retardative between 20 a club or other shaft undergoing test and a section of the variably driven shaft system upon a section of which the disc 50 is secured; and the brake organization comprising drum 49 and band 55 essentially constitu- 25 tes an automatic means for bringing a section of said shaft system to rest, preliminarily to a repetition of the described move- 30 ments, at the same or a different rate, and with the club or other shaft in the same or an altered position.

It will be seen that the effect of the rotation of the sleeve 26, or its equivalent, in bending or twisting or actually breaking a shaft must depend not only upon the maximum rotational velocity imparted to said sleeve but to the manner of starting and stopping and also upon the inclination of the club and the point at which the club head 84, or its equivalent, may stroke; and also upon the character and freedom of movement of said ball, or an equivalent yieldable obstruction,—when employed. It will accordingly be understood that my invention provides not only means for holding a club 45 in various positions and advancing the same at various rates but also that the ball-supporting means may be variously positioned, and that free or attached balls of various types may be employed, in order to subject either club shafts or club heads to any desired tests; and the advance of balls 99 may be so timed in any desired way with reference to the described swinging of clubs.

It will be apparent from the foregoing 55 description, that several methods of accumulating and interpreting data upon the relative durability and driving strengths of golf clubs may be used in connection with this machine. The clubs may be placed in the machine and used in connection with rubber or metal balls or with the construction shown in Fig. 12, until they fail. The position and driving power used being the same in all comparative cases, the number of strokes

prior to failure for the clubs will be a 65 measure of their relative durability.

The measurement of the distances which the same ball, or balls of the same weight and resilience, are driven by different clubs under the same conditions will determine 70 the relative driving power or "life" of the different clubs.

Other tests for determining the action of various clubs when placed in abnormal positions, and tests in determining the most 75 efficient shape and angle of heads for various conditions may be conducted with dependable and measurable accuracy.

Although I have herein described a single complete embodiment of my invention, suggesting alternative constructions and modes of use, it should be understood not only that various features thereof may be independently used but also that numerous modifications might be made, by those skilled in 80 the art to which this case relates, without the slightest departure from the spirit and scope of this invention, as the same is indicated above and in the following claims.

I claim as my invention:

1. In means for testing the behavior of 90 golf clubs when swung through arcs: means for releasably securing a golf club at an adjusted angle and elevation relative to a fixed point; and adjustable means for imparting to said club, through said securing means, successive strokes, substantially imitating the strokes of actual play.

2. In means for testing the behavior of 95 golf clubs when swung through arcs: means for releasably securing a golf club at an adjusted angle and elevation relative to a fixed point; adjustable mechanical means for imparting to said club, through said securing means, successive strokes, substantially imitating 100 the strokes of actual play; and means for supporting a yieldable obstruction in the path of said club.

3. In means for testing the behavior of 110 golf clubs when swung through arcs: means for releasably securing a golf club at an adjusted angle and elevation relative to a fixed point; and means for imparting to said club, through said securing means, successive strokes, substantially imitating the strokes 115 of actual play,—said stroke-imparting means including a uniformly rotated shaft, and means for transmitting a non-uniform movement therefrom to said securing means.

4. In means for testing the behavior of 120 golf clubs when swung through arcs: means for releasably securing a golf club at an adjusted angle and elevation relative to a fixed point; a shaft section supporting said securing means and means for imparting to said club, through said securing means, successive strokes, substantially imitating the strokes 125 of actual play,—said stroke-imparting means

- including a uniformly rotated shaft, and means for transmitting a non-uniform movement therefrom to said securing means, a cam-operated clutch being interposed between said uniformly rotated shaft and said shaft section by which said securing means are carried. 65
5. In means for testing the behavior of golf clubs when swung through arcs: means for releasably securing a golf club at an adjusted angle and elevation relative to a fixed point; and means for imparting to said club, through said securing means, successive strokes, substantially imitating the strokes of actual play, said stroke-imparting means including a uniformly rotated shaft, and means including a driven shaft section for transmitting a non-uniform movement therefrom to said securing means, a brake being interposed between said uniformly rotated shaft and said shaft section. 70
- 10 6. In means for testing the behavior of golf clubs when swung through arcs: means for releasably securing a golf club at an adjusted angle and elevation relative to a fixed point; and means for imparting to said club, through said securing means, successive strokes, substantially imitating the strokes of actual play, said stroke-imparting means including a uniformly rotated shaft, and means including a driven shaft section for transmitting a non-uniform movement therefrom to said securing means,—a slip-limiting means being interposed between said driven shaft section and said securing means. 75
- 15 7. In means for testing a shaft: a pivoted holding organization; releasable means for securing said shaft at a desired angle to said holding organization; means for supporting a yieldable obstruction in the path of a part on said shaft; and means for so moving said pivoted holding element as to produce a predetermined contact between said part and said obstruction. 80
- 20 8. In means for testing a shaft which carries an impact member: a pivoted movable holding organization; releasable means for securing said shaft at a desired angle to said holding organization; means for supporting a yieldable obstruction in the path of said impact member; and means for so moving said movable holding element as to produce a predetermined contact between said impact member and said obstruction,—said moving means comprising a motor and a mechanical train driven thereby and speed-changing means interposed in said mechanical train. 85
- 25 9. In a shaft-testing machine, means for releasably holding a golf club at an adjusted angle and elevation relative to a fixed point; and mechanically operated means for there- 90
- 30 by swinging said club in such manner as to simulate a playing stroke. 95
10. In a shaft-testing machine, means for releasably holding a golf club at an adjusted angle and elevation relative to a fixed point; mechanically operated means for thereby swinging said club in such manner as to simulate a playing stroke; and means for supporting a ball in such position as to be struck in a desired manner; during said stroke. 100
- 15 11. In a shaft-testing machine, a plate member provided with means for releasably holding a golf club at an adjusted angle and elevation relative to a fixed point; and mechanically operated means for thereby swinging said club in such manner as to simulate a playing stroke,—said swinging means comprising a sleeve integral with said plate. 105
- 20 12. In a shaft-testing machine, means for releasably holding a golf club; and means for thereby swinging said club in such manner as to simulate a playing stroke, said swinging means comprising a uniformly rotated shaft and a sectional driven shaft system disposed parallel therewith; and means interconnecting said constantly rotated shaft and a section of said driven shaft system comprising a crank, a wrist pin carried by said crank, and a member provided with a cam slot, to receive said wrist pin. 110
- 25 13. A golf club testing machine comprising: a uniformly rotated shaft; a sectional driven shaft system; means carried by a section thereof for releasably engaging a club; and means for transmitting motion thereto, at controllably varied rates, from said uniformly rotated shaft. 115
- 30 14. A golf club testing machine comprising: a uniformly rotated shaft; a sectional driven shaft system; means carried by a section thereof for releasably engaging a club; means for transmitting motion to said driven shaft system, at controllably varied rates, from said uniformly rotated shaft; a yieldable obstruction, adapted to be struck by said club; and means for supporting said yieldable obstruction. 120
- 35 15. A golf club testing machine comprising: a uniformly rotated shaft; a sectional driven shaft system; means carried by a section thereof for releasably engaging a club; means for transmitting motion to said driven shaft system, at controllably varied rates, from said uniformly rotated shaft; a yieldable obstruction, to be struck by said club; and means for advancing said obstruction. 125
- 40 16. A golf club testing machine comprising: a uniformly rotated shaft; a sectional driven shaft system; means carried by a section thereof for releasably engaging a

club; and means for transmitting motion to said driven shaft system, at controllably varied rates, from said uniformly rotated shaft—said transmitting means including an intermediate shaft, provided with a slotted arm; and means for transmitting motion therefrom to said driven shaft system.

17. A golf club testing machine comprising: a uniformly rotated shaft; a sectional driven shaft system; means carried by a section thereof for releasably engaging a club; and means for transmitting motion from said uniformly rotated shaft, to said driven shaft system, at controllably varied rates,—said shaft system including a crank driven section.

18. A golf club testing machine comprising: a uniformly rotated shaft; a sectional driven shaft system; means carried by a section thereof for releasably engaging a club; and means for transmitting motion from said uniformly rotated shaft, to said driven shaft system, at controllably varied rates,—said shaft system including a clutch-driven section.

19. A golf club testing machine comprising: a uniformly rotated shaft; a sectional driven shaft system; means carried by a section thereof for releasably engaging a club; and means for transmitting motion from said uniformly rotated shaft, to said driven shaft system, at controllably varied rates,—said shaft system including a clutch-driven section provided with adjustable cam means adapted to govern the fraction of a cycle of rotation imparted to said club engaging means.

20. A golf club testing machine comprising: a uniformly rotated shaft; a sectional driven shaft system; means carried by a section thereof for releasably engaging a club; and means for transmitting motion from said uniformly rotated shaft, to said driven shaft system, at controllably varied rates,—said shaft system including a brake-carrying section.

21. A golf club testing machine comprising: a uniformly rotated shaft; a sectional driven shaft system; means carried by a section thereof for releasably engaging a club; and means for transmitting motion from said uniformly rotated shaft, to said driven shaft system, at controllably varied rates,—said shaft system including a brake-carrying section provided with means for varying the application of a brake relatively to a cycle of rotation.

22. A golf club testing machine comprising: a uniformly rotated shaft; a sectional driven shaft system; an intermediate shaft adapted to receive rotation from said uniformly rotated shaft; means for transmitting motion from said intermediate shaft to said driven shaft at controllably varied rates, said driven shaft system being movable to and from a co-axial relation with said intermediate shaft; and means carried by a section of said driven shaft system for releasably engaging a club.

In testimony whereof, I have hereunto set my hand at Los Angeles, California, this 11th day of April, 1927.

GEORGE E. BARNHART.
